(57) **CLAIM**

I claim the ornamental design for a multi-function tile saw, substantially as shown.

DESCRIPTION

FIG. 1 is a perspective view of the multi-function tile saw. FIG. 2 is a side view of the multi-function tile saw. FIG. 3 is an opposite side view of the multi-function tile saw. FIG. 4 is a top view of the multi-function tile saw. FIG. 5 is a bottom view of the multi-function tile saw. FIG. 6 is a rear view of the multi-function tile saw; and, FIG. 7 is a front view of the multi-function tile saw.
